CLAIM

The ornamental design for a tote bag, as shown and described herein.

DESCRIPTION

FIG. 1 is a front perspective view of a tote bag for carrying selected items;

FIG. 2 is a top view of the bag shown in FIG. 1;

FIG. 3 is a front view of the bag shown in FIG. 1;

FIG. 4 is a side view of the bag shown in FIG. 1;

FIG. 5 is the other side view of the bag shown in FIG. 1;

FIG. 6 is a rear view of the bag shown in FIG. 1; and,

FIG. 7 is a bottom view of the bag shown in FIG. 1.

The straps are shown broken away in FIGS. 1, 3, 4, 5, and 6, to indicate indeterminate length.
